UNITED STATES PATENT OFFICE.

MARY COHN, OF NEW YORK, N. Y.

DESIGN FOR A TOY CIRCUS WAGON.

Application filed July 5, 1928. Serial No. 27,378. Term of patent 3½ years.

To all whom it may concern:

Be it known that I, MARY COHN, a citizen of the United States of America, residing in New York, county and State of New York, have invented a new, original, and ornamental Design for Toy Circus Wagon, of which the following is a specification, reference being had to the accompanying drawing, forming part thereof, in which—

I claim:

The ornamental design for a toy circus wagon, as shown.

MARY COHN.
